SPECIFICATION forming part of Design No. 20,196, dated October 7, 1890.

Application filed July 25, 1890. Serial No. 359,970. Term of patent 3½ years.

To all whom it may concern:

Be it known that we, MAIER WEINSCHENK and WILLIAM BOLDENWECK, citizens of the United States, residing at Chicago, in the county of Cook and State of Illinois, have invented and produced a new and original Design for Medals, of which the following is a specification, reference being had to the accompanying drawing, forming a part thereof.

10 Our invention relates to a design for one face of a medal.

The drawing represents a front view of the design. The upper portion consists of a pictorial representation of the signing of the Declaration of Independence. Immediately below this picture is a scroll extending across the face of the medal. Occupying the lower central portion of the design and partly overlapping the scroll and picture described above is an eagle surmounting a shield, and at each side of the shield and eagle is a portrait, as shown.

What we claim is—

The design herein shown and described for a medal, the same comprising a pictorial representation on the upper portion of one face of the medal of the signing of the Declaration of Independence, a scroll extending across the middle portion of the said face, an eagle and shield occupying the central lower portion, a portrait at the left of the eagle and shield, and a portrait at the right of the eagle and shield, as set forth.
